UNITED STATES PATENT OFFICE.

FOREST H. HARTZELL, OF DAYTON, OHIO, ASSIGNOR TO THE CROWN HARDWARE MANUFACTURING COMPANY, OF DAYTON, OHIO, A CORPORATION OF OHIO.

MUSICAL APPARATUS.

1,088,223.

Specification of Letters Patent.

Patented Feb. 24, 1914.

Application filed November 13, 1911. Serial No. 659,885.

To all whom it may concern:

Be it known that I, FOREST H. HARTZELL, a citizen of the United States, residing at Dayton, in the county of Montgomery and 5 State of Ohio, have invented certain new and useful Improvements in Musical Apparatus, of which the following is a specification.

My invention relates to musical instruments and particularly to mechanical piano-players.

The invention relates to the pneumatic type of mechanical players wherein the operation of the device is controlled by a 15 traveling perforated master sheet and relates especially to means for controlling the movement of the master sheet during the winding and rewinding operation and also for laterally shifting said master sheet to 20 bring the perforations into registry with predetermined air passages or ducts.

The object of the invention is to simplify the structure as well as the means and mode of operation of such devices whereby they 25 will not only be cheapened in construction but will be more positive in operation, more efficient in use, easily and quickly adjusted and unlikely to get out of repair.

A further object of the invention is to 30 provide an improved alternately operating brake mechanism controlling the winding and rewinding shafts which will be unaffected by the lateral adjustment of the master sheet.

35 A further object of the invention is to provide improved means for quickly and readily adjusting the master sheet laterally through an extended range of movement whereby the perforations of the master 40 sheet may not only be brought into registry with the air passages or ducts but may be adjusted to register with any one of the series of said ducts whereby the musical composition represented by the perforations 45 of such master sheet may be played in any one of several different keys.

With the above primary and other incidental objects in view as will more fully appear in the specification the invention consists of the features of construction, the 50 parts and combinations thereof and the

mode of operation or their equivalents as hereinafter described and set forth in the claims.

Referring to the drawings Figure 1 is a 55 front elevation of a portion of the assembled machine embodying the control mechanism forming the subject matter hereof, in its winding or normal operating position. Fig. 2 is a detail view similar to Fig. 1 showing 60 the brake or control mechanism in the rewinding position. Fig. 3 is a detail perspective view of the mechanism for shifting the master sheet laterally in relation to the perforations or orifices of the tracker 65 bar.

Like parts are indicated by similar characters of reference throughout the several views.

In the drawing 1 is the main frame or 70 housing and 2 is the tracker bar therein having in its surface the perforations 3 forming the orifices of the several air passages or ducts which are opened and closed in predetermined sequence by the movement 75 of the perforated master sheet 4 there across. During this operative movement the master sheet is wound from the roll 5 to the roll 6 with its perforations in registry with the orifices 3 in the tracker bar 2. The winding 80 and rewinding mechanism is actuated by an air motor 7 shown at the right in Fig. 1 but which forms no part of the present invention. Secured to the side of the housing 1 is a frame comprising the parallel lateral 85 members 8 connected by the transverse ties 9 within which are journaled in suitable bearings the winding shaft 10 and the rewinding shaft 11. The shafts 10 and 11 are preferably reduced or pointed at their extremities and are provided with thrust bearing 90 as well as journal bearings in the lugs 12 carried on the frame member 8. Journaled in the frame members 8 between the shafts 10 and 11 is the main drive shaft 13 95 driven by the sprocket chain 14 from the actuating motor 7. Carried by the drive shaft 13 is a gear pinion 15 meshing with a gear 16 mounted upon the winding shaft 10. There is loosely journaled upon the drive 100 shaft 13 a sprocket wheel 17 connected by a sprocket chain 18 with a corresponding

sprocket 19 upon the rewinding shaft 11. The rewinding shaft 11 also carries a disk 20 forming a part of a brake mechanism hereafter mentioned.

- 5 The gear pinion 15 is movable laterally into and out of engagement with the gear 16 and when disengaged from the gear 16 it is adapted to engage with the sprocket 17 by means of intermediate clutch mechanism 10 whereby said sprocket 17 will be driven. The gear pinion 15 may be slidingly mounted upon the main shaft 13 and interengaged therewith by means of the usual feather or key whereby said gear pinion 15 may slide 15 upon the shaft 13 or said gear pinion 15 may be secured rigid upon the shaft 13 and said shaft reciprocated within its bearings in addition to its revoluble movement. The sprocket 17 is held against lateral movement in unison with the shaft or with the gear pinion 15 by means of a stud 21 the head of which engages in a peripheral groove 22 in the hub of said sprocket. In the drawing the gear pinion 15 and the 20 sprocket wheel 17 have been shown as provided with studs or pins 23 which interengage one with the other when the pinion 15 has been shifted laterally out of engagement with the gear 16 and by their engagement drive the sprocket 17 as the shaft 13 is rotated. It is obvious that any suitable 25 form of shifting clutch mechanism may be substituted for the construction shown. Pivoted upon a bracket 24 carried by one 30 of the side members 8 is a shift lever 25 having a stud 26 which engages a peripheral groove in the gear pinion 15 to shift said gear pinion into and out of engagement with the sprocket and gear.
- 35 Pivottally supported upon the bracket 24 are two oppositely extending brake levers 27 and 28 each carrying a brake shoe 29. The brake shoe 29 of the brake lever 27 is adapted to engage the friction disk 20 carried upon the rewinding shaft 11 while the corresponding brake shoe of the other lever 28 engages the side of the gear 16 carried upon the winding shaft 10. The brake levers 27 and 28 are connected with the shift 40 lever 25 by springs 30 and 31 on opposite sides of the pivoted point of said shift lever. When the shift lever is moved to the position shown in Fig. 1 causing the gear pinion to interengage with the gear 16 to rotate the winding shaft 10, the spring 30 is placed under tension and draws the shoe of the brake lever 27 into frictional contact with the disk 20 thereby retarding the rotation of the shaft 11 and the master sheet 45 4 is withdrawn from the roll 5 and wound upon the roll 6 by the rotation of the winding shaft 10. The same movement of the shift lever 25 relaxes the tension upon the spring 31 thereby releasing the pressure of

the shoe 29 of the brake lever 28 upon the gear 16 leaving the winding shaft 10 free to rotate. During this winding operation the winding shaft 10 is driven from the main drive shaft 13 through the gears 15 and 16. The rewinding shaft 11 being at the same time disconnected from the drive shaft 13 by the disengagement of the gear 15 from the sprocket 17 and the rewinding shaft 11 only rotates under the influence of the perforated sheet 4 as it is withdrawn from the roll 5 and against the frictional resistance of the brake shoe 29 upon the disk 20. After the perforated sheet has been passed from the roll 5 to the roll 6 across the perforated tracker bar 2 and it is desirous to 50 return the perforated sheet 4 to the original roll 5 the shift lever 25 is oscillated as shown in Fig. 2 thereby shifting the gear pinion 15 out of engagement with the gear 16 and into engagement with the sprocket 17 with which it is engaged by intermediate clutch teeth or by the studs or pins 23 as shown in the drawing thereby causing the sprocket 17 to rotate in unison with the drive shaft 13. The same movement of the 55 shift lever 25 relaxes the tension of the spring 30 thereby permitting the brake lever 27 to oscillate to release the frictional pressure of its shoe 29 upon the disk 20 and at the same time the spring 31 is placed under tension thereby drawing the shoe 29 of the brake lever 28 into frictional engagement with the gear 16 upon the winding shaft 10. The rewinding shaft 11 is driven from the sprocket 17 through the chain 18 and sprocket 19 at an increased rate of speed due to the difference in size of the 60 sprockets 17 and 19. The shoe 29 of the brake lever 27 being released from frictional engagement with the disk 20 permits 65 the shaft 11 to rotate freely while at the same time the shoe of the brake lever 28 engaging the gear 16 retards the rotation of the shaft 10 as the perforated sheet 4 is withdrawn from the roll 6 and returned to 70 the roll 5 thereby keeping the master sheet 4 under tension. It will thus be seen that the operation of shifting the gear pinion 15 into and out of engagement with the gear 16 automatically reverses the brake mechanism to retard either the winding shaft 10 or the rewinding shaft 11 according to the direction of movement of the master sheet.

75 The extremities of the shafts 10 and 11 project within the housing 1 and each carries a sleeve 32 slidingly mounted upon the extremity of the shaft but engaged therewith by a suitable key or other connection whereby said sleeve 32 may reciprocate upon the shafts 10 and 11 but will rotate therewith. The rolls 5 and 6 are detachably engaged with the sleeves 32 in any of the well known manners as now used for connect-

ing the rolls of such mechanical players with their supporting and drive shafts. Each of the reciprocating sleeves 32 is provided with a series of parallel peripheral grooves 33 forming an annular gear rack. Journalized in suitable bearings carried in the housing 1 is a shaft 34 arranged at right angles to the shafts 10 and 11 and carrying gear pinions 35 which mesh with the annular gear teeth formed in the reciprocating sleeves 32 by the parallel peripheral grooves 33. At its lower extremity the shaft 34 is provided with a lateral arm 36 connected by a link 37 with one arm of a pivoted lever 38 secured to the base of the housing 1. The lever 38 carries a stud 39 projecting through a suitable arcuate slot in the base of the housing 1 and engaged by a thumb nut 40 whereby the lever 38 may be secured in its adjusted position. By oscillating the lever 38 the shaft 34 is correspondingly oscillated thereby partially rotating gear pinions 35 carried by said shaft 34 which by their engagement within the parallel peripheral grooves 33 of sleeves 32 will reciprocate said sleeves 32 upon the shafts 10 and 11. The continuous parallel annular grooves 33 of the sleeves 32 permit the sleeves 32 to rotate independent of the gear pinions 35 while said gear pinions 35 maintain their engagement with the grooves 33 and thereby retain the sleeves 32 in their adjusted positions. The gear pinions 35 in no way interfere with the rotation of the sleeves 32. By rotating the gears 35 to shift the sleeves 32 longitudinally upon the shaft extremities the rolls 5 and 6 may be shifted laterally to bring the perforations of the master sheet 4 to registry with the orifices 40 of the air conduits or passages and the sheet may be shifted through a range of several of the conduits or passages enabling the operator to change the key in which the composition is being played. The shifting movement of the rolls is compensated for by a yielding or spring pressed bearing with which the opposite trunnion of the roll engages. Such yielding bearing may be of ordinary construction and forms no part of the present invention, and therefore has not been shown in the drawing.

It will be obvious that the adjustment of the master sheet or perforated sheet may be made very quickly and that such adjustment will in no way interfere with the driving mechanism or vary the pressure or frictional engagement of shoes 29 with the disk 20 and gear 16.

From the above description it will be apparent that there is thus produced a device of the character described possessing the particular features of advantage before enumerated as desirable but which obviously is susceptible of modification in its form,

proportions, detailed construction and arrangement of parts without departing from the principle involved or sacrificing any of its advantages.

It is to be further understood that the means and mechanism herein described illustrates but one mode of putting this invention into effect and that the invention is therefore claimed broadly in any of its possible forms or modifications within the scope of the appended claims.

Having thus described my invention I claim,

1. In a winding mechanism, a receiving roll and a supply roll, winding and rewinding shafts with which the rolls are connected, a drive shaft adapted to alternately actuate the winding and rewinding shafts, brake devices for the winding and rewinding shafts each independent of the other adapted to retard the rotation thereof, a lever pivoted at a medial point whereby said lever will comprise oppositely extending arms and operative connections between the brake devices and the lever on opposite sides of the pivotal point of the lever whereby as said lever is oscillated one of the brake devices will be moved into operative position and the other brake device relaxed, substantially as specified.

2. In a winding mechanism, a receiving roll and a supply roll, winding and rewinding shafts with which the rolls are connected, a drive shaft adapted to alternately actuate the winding and rewinding shafts, disks carried by the winding and rewinding shafts, two independent pivoted brake levers each capable of oscillation independent of the other carrying shoes adapted upon the oscillation of the levers to engage said disks, a pivoted control lever, an elastic link connecting one of the brake levers with the control lever at one side of its pivotal point, and a second elastic link connecting the other brake lever with the control lever at the opposite side of its pivotal point whereby at each oscillation of the control lever one of the elastic links will be placed under tension and the other elastic link released, substantially as specified.

3. In a winding mechanism, a receiving roll and a supply roll, winding and rewinding shafts with which the rolls are connected, a drive shaft adapted to alternately actuate the winding and rewinding shafts, a pivoted shift lever adapted to alternate the driving connections of the shafts, an independent brake device for each of the shafts, each of said devices being capable of oscillation independent of the other, and connections between said shift lever and brake devices connecting the brake devices with the shift lever at opposite sides of the pivotal point thereof whereby the movement of the

shift lever to connect the drive shaft with either of the winding or rewinding shafts will automatically release the brake mechanism from the shaft with which the drive shaft is to be connected and apply it to the other of said shafts, substantially as specified.

In testimony whereof, I have hereunto set my hand.

FOREST H. HARTZELL.
